VAPORPROOF HAND PORTABLE

Filed June 24, 1927

Inventor:
Francis C. Kollath
By
Chester E. Warner
Attorney.

UNITED STATES PATENT OFFICE

FRANCIS C. KOLLATH, OF CHICAGO, ILLINOIS

VAPORPROOF HAND PORTABLE

Application filed June 24, 1927. Serial No. 201,063.

My invention relates to hand portable lamps, and especially to that class commonly called "vapor proof hand portables", and which are particularly designed for use in places where injurious gases and vapors would corrode the socket contacts and other exposed current carrying parts of the ordinary unprotected hand portable, thereby decreasing the efficiency of the device if not destroying its usefulness entirely.

One of the objects of my invention is to provide a hand portable in which all of the electrical contacts of the socket and lamp are inclosed in a vapor proof chamber formed by the inclosing globe and handle.

Another object of my invention is to provide, with a minimum number of parts, a cushion support for both globe and lamp, and thereby providing a device which may be subjected to rough usage and careless handling with full protection to otherwise easily breakable parts.

Another object is to provide a device which is cheap to manufacture, easy to assemble, and of few parts, and in this connection it will be noted that the device as illustrated consists of only four main elements, that is, the handle, socket, globe, and guard, and providing with these few parts, full protection for the device, from both shock and injurious vapors and gases.

Realizing that my invention may be varied in its physical embodiment without departing from the spirit of the invention, I desire it to be understood that the specific construction and form herein shown is to be taken as illustrative and not in a limited sense.

In the accompanying drawings, like portions of the device are designated by like characters throughout the several figures.

Figure 1 is a side elevation of my invention, with a portion of the handle, guard, and globe broken away to more effectively illustrate the details of construction.

Figure 2 is a detail sectional view illustrating one form of construction when the globe clamping means is independent of the guard.

Referring now to the drawings in detail, my invention as illustrated, comprises a handle 1 having an enlarged portion 2, with a chamber

3 therein to receive the socket 4. This socket is of the ordinary commercial type and is well known, and therefore it need not be described here except to say that it is of molded insulation and has a threaded shell and center contact therein to receive the lamp. The conductors 6 are molded or cemented in the insulation to form a gas and vapor proof socket except at the front end where the lamp is inserted.

The handle 1 which supports the socket, as well as the globe and guard, consists of a single piece of flexible and resilient material, preferably comparatively soft molded rubber, which absorbs any shocks or jars incidental to rough usage.

The handle is provided with an internal collar 7 adapted to fit into a corresponding annular groove 8 in the socket 4. On the outside of the handle and directly over the internal collar 7 is an annular groove 9 to accommodate the split clamping ring 10 of the wire guard 11. This guard is of the usual split construction, the two halves being sprung apart at the bottom to receive the handle. The individual wires 12 of the guard are welded or otherwise secured to the two halves of the split ring 10.

A flange 13 having an outwardly extending annular ring portion 14, to receive the globe 15, is formed integral with the handle. The outwardly extending portions 16 of the guard wires 12 form a seat for the flange 13 to prevent too great a movement of the globe due to the resiliency of the flange.

The annular ring 14 is internally threaded as shown, to receive the globe which is of standard design. In the outside of the ring 14, and directly over the internally threaded portion, is an annular groove 17 to receive the split ring 18, which, in the preferred form, is fastened by welding or other suitable means to the wires 12 of the guard.

It will be readily understood, from an inspection of the drawings, that when the socket containing the lamp is inserted in the handle and the globe is screwed into the ring 14, split rings 10 and 18 may be clamped in place in their respective grooves by any suitable means such as the screws 19 and 20, thereby

forming an effective gas and vapor proof seal between the handle and socket, and also between the annular ring 14, which is integral with the handle, and the globe 15. All this being accomplished with a minimum of parts.

10 A coil spring 21 may be provided, if desired, between the outer end of the guard and the globe 15, to prevent undue outward movement of the globe. This is especially desirable when the split clamping ring 18 is not fastened to the guard wires, as in the construction shown in the modified form in Figure 2.

15 Having thus fully described my invention, I claim as new and desire to secure by Letters Patent:

20 1. A vapor proof shock absorbing electric lighting device comprising a single piece of soft rubber having a chamber therein to receive a socket, a socket in said chamber to support an electric lamp, a globe around said lamp and supported in said rubber, said single piece of soft rubber cooperating with said socket and said globe to form a combined vapor proof and shock absorbing means therebetween, and means for clamping said rubber around said socket and said globe.

25 2. An electric lighting device comprising a handle having a chamber therein to receive a socket, a snugly fitting socket in said chamber to receive an electric lamp, a globe around said lamp, and a guard around said globe, shock absorbing and vapor proofing means between said socket and said globe and supporting said globe, shock absorbing and vapor proofing means between said globe and said guard and supporting said guard, all of said means being integral with said handle, and a clamp on said guard and around said handle and clamping all of said means snugly around their cooperating parts.

30 3. An electric lighting device comprising a handle having a chamber therein to receive a socket, a snugly fitting socket in said chamber to support an electric lamp, a globe around said lamp, shock absorbing and vapor proofing means between said socket and said globe and integral with said handle, shock 35 absorbing supporting means extending around said globe and integral with said handle, and clamping means for clamping all of said parts in shock absorbing and vapor proofing relation and including means cooperating with the globe supporting means to hold said support against longitudinal movement.

35 In witness whereof, I have hereunto subscribed my name.

40 FRANCIS C. KOLLATH.
